PRESS TYPE ASSEMBLED FAN

TECHNICAL FIELD

The present disclosure relates to the field of heat sink technologies, and in particular, to a press type assembled fan.

BACKGROUND

With a continuous development of computer technology, personal computers are gradually entering households and becoming an indispensable and important component of people's daily lives. And personal computers have gradually evolved from customized machines from major brand manufacturers to DIY being the mainstream; nowadays, people's economic conditions also allow them to upgrade their personal computers, and there are gradually emerging DIY enthusiasts like hardware enthusiasts.

Water cooling is also a commonly used accessory in computer hardware DIY, which is generally divided into integrated water cooling or split water cooling. Compared to split type water cooling, the integrated water cooling has a lower cost and is also the water-cooling type with the highest installed capacity. The integrated water cooling generally consists of a cold exhaust, a fan, a water pipe, and a cold head, and the fan is installed on the cold exhaust and dissipates heat from the coolant flowing through the cold exhaust. For large-sized (240 mm or 360 mm) water-cooling systems, the commonly used method on the market is to connect two or three fans with a standard size (120 mm) to assemble. For example, the utility model patent with application number of CN20211126482.7 and titled with a magnetic suction fan set, a magnetic suction is used for connection. As the fans are connected by the magnetic suction, fixed parts are required to limit a horizontal position of the fans. However, due to the small force of the magnetic suction, this type of fan has a problem of poor assembly stability during use.

With a continuous development of computer technology, personal computers are gradually entering households and becoming an indispensable and important component of people's daily lives. And personal computers have gradually evolved from customized machines from major brand manufacturers to DIY being the mainstream; nowadays, people's economic conditions also allow them to upgrade their personal computers, and there are gradually emerging DIY enthusiasts like hardware enthusiasts.

Water cooling is also a commonly used accessory in computer hardware DIY, which is generally divided into integrated water cooling or split water cooling. Compared to split type water cooling, the integrated water cooling has a lower cost and is also the water-cooling type with the highest installed capacity. The integrated water cooling generally consists of a cold exhaust, a fan, a water pipe, and a cold head, and the fan is installed on the cold exhaust and dissipates heat from the coolant flowing through the cold exhaust. For large-sized (240 mm or 360 mm) water-cooling systems, the commonly used method on the market is to connect two or three fans with a standard size (120 mm) to assemble. For example, the utility model patent with application number of CN20211126482.7 and titled with a magnetic suction fan set, a magnetic suction is used for connection. As the fans are connected by the magnetic suction, fixed parts are required to limit a horizontal position of the fans. However, due to the small force of the magnetic suction, this type of fan has a problem of poor assembly stability during use.

In order to solve the above problems, an embodiment discloses a press type assembled fan, as shown in FIGS. 1 and 2. The fan includes a frame 100 and fan blades 118 installed on the frame 100. One side of the frame 100 is provided with a first electrical connector 103 and slidably provided with a first push plate 102, an outer end face of the first push plate 102 is rotatably connected with a fastener 101; the other side of the frame 100 is provided with a second electrical connector 106 and slidably provided with a second push plate 105. The second push plate 105 is provided with a buckle 104 corresponding to the fastener

101, the fastener 101 is configured to detachably connect to the buckle 104; when the push plate slides along one side of the frame 100, the first fastener 101 rotates along the push plate.

5 In an implementation, the first electrical connector 103 is an electrical contact piece, and the second electrical connector 106 is a Pin needle or an electrical contact elastic piece; the first push plate 102 is pushed to cause the fastener 101 rotates and protrudes from the frame 100. One side of 10 the fan is aligned with and inserted into the other side of another fan to achieve a fit between the fastener 101 and the buckle 104. The structure of the fastener 101 and buckle 104 can be referred to FIGS. 1 and 2. In an implementation, the fastener 101 and buckle 104 are clamp connection, and a 15 shrapnel 117 is provided on an inner side of the frame 100 near the buckle 104. After the fastener 101 is clamped with the buckle 104, the shrapnel 117 abuts against the fastener 101 to improve a stability of a cooperation between the fastener 101 and buckle 104.

20 In an implementation, an outer end face of the first push plate 102 is provided with a rack 107, the fastener 101 is provided with a gear 108, and the gear 108 meshes with the rack 107. When the first push plate 102 is pushed, the rack 107 drives the gear 108 to rotate, thereby achieving an effect 25 of driving the fastener 101 to rotate.

In an implementation, the outer end face of the first push plate 102 is further provided with a protrusion 109, and one side of the frame 100 is provided with a first through-hole 110 configured to expose the protrusion 109 and a second through-hole 111 configured to expose the fastener 101. By 30 moving the protrusion 109, the first push plate 102 can be controlled to slide left and right within the frame 100.

35 In an implementation, one side of the frame 100 is provided with a first recess 112, and the other side of the frame 100 is provided with a second recess 113. The first electrical connector 103 is provided in the first recess 112, and the second electrical connector 106 is provided in the second recess 113. Through the above structure, an embedded structure design of the first electrical connector 103 and the second electrical connector 106 is achieved.

40 This embodiment further discloses a fan set, and the structure is shown in FIGS. 3 to 5. The fan set includes a plurality of fans, adjacent fans are detachably connected through the fastener 101 and the buckle 104, and electrically connected through the first electrical connector 103 and the second electrical connector 106.

45 In an implementation, one side of the second push plate 105 that is protruded from the frame 100 is provided with a button 114. After the gear fastener 101 is matched with the buckle 104, the second push plate 105 is pushed by pressing the button 114 so as to separate the buckle 104 from the fastener 101, thereby achieving a separation between adjacent fans. In addition, an elastic member 115 is connected 50 between the second push plate 105 and the frame 100, which can be reset after pressing the second push plate 105, rendering it convenient for next use.

55 In an implementation, the fan set further includes a protective shell 116, which can be detachably connected to the other side of the outermost fan. From FIG. 3, it can be seen that due to a portion of the second electrical connector 106 protruding from the frame 100, the protective shell 116 can cover the second connector of the outermost fan, thereby playing a role in protecting the second electrical connector 106.

60 In summary, the press type assembled fan in this embodiment, adjacent fans are detachably connected through a cooperation between the fastener 101 and buckle 104. After 65

5

the fastener 101 and the buckle 104 are corporate, the first electrical connector 103 contacts the second electrical connector 106 to achieve an electrical connection; besides, by pressing the first push plate 102, the rotation and folding of the fastener 101 can be achieved, rendering the fan more suitable for individual use or storage. Compared with the assembly ways of existing technologies, the present disclosure is easier to assemble, has higher assembly stability, and will not be inconvenient to store due to the fastener 101 that is protruded.

Finally, it should be noted that the above embodiments are only used to illustrate the technical solution of the present disclosure, and not to limit the protection scope of the present disclosure. Although detailed explanations of the present disclosure have been provided with reference to preferred embodiments, those skilled in the art should understand that modifications or equivalent replacements can be made to the technical solution of the present disclosure without departing from the essence and scope of the technical solution of the present disclosure.
